UNITED STATES PATENT OFFICE.

DAVID S. JACOBUS, OF JERSEY CITY, NEW JERSEY, ASSIGNOR TO THE BABCOCK & WILCOX COMPANY, OF BAYONNE, NEW JERSEY, A CORPORATION OF NEW JERSEY.

PROTECTION MEANS FOR SOOT-BLOWING ELEMENTS.

Application filed October 15, 1920. Serial No. 417,194.

Soot-blowing elements, as is well known, are commonly used for removing deposit which accumulates on the boiler tubes of steam boilers. The difficulty has been experienced, however, that such elements have a comparatively short life, as it is necessary to install them where they are subjected to intense heat with consequent injury to the elements.

10 The object of my present invention is the provision of means for cooling the soot-blowing elements, and thereby greatly increasing the life thereof.

My invention will best be understood by 15 reference to the accompanying drawings, in which like reference characters indicate like parts, and in which Figure 1 is a vertical sectional elevation of a steam boiler embodying my invention; Fig. 2 is a fragmentary section illustrating, on a larger scale than Fig. 1, the position of the soot-blowing element with reference to the associated parts; Fig. 3 is a sectional elevation taken at right-angles to Fig. 2; Fig. 4 is an enlarged 20 sectional view, similar to Fig. 2, but showing a modified form of my invention; Fig. 5 is a vertical sectional elevation taken through Fig. 4 and at right-angles thereto; Fig. 6 is a sectional view similar to Fig. 2, 25 but showing still another modified form of my invention; Fig. 7 is a section taken along the line 7—7 of Fig. 6, and Fig. 8 is a perspective view of one of the removable blocks which, with the remainder of the protecting 30 member, surrounds the soot-blowing element.

Referring, now, to the drawings, 10 are the inclined water tubes of a steam boiler in which I have illustrated my invention, the 35 tubes preferably being divided into an upper bank 10^a and a lower bank 10^b, the two banks being spaced apart to form a secondary combustion chamber 11 therebetween. The ends of the boiler tubes are connected to 40 uptake and downtake headers 12 and 13, respectively, the uptake headers being connected by tubes 14 and 15 to the steam and water drum 16, while the downtake header 13 is connected to the drum by tubes 17. In 45 the boiler here shown, the upper bank 10^a of tubes is divided into two banks, somewhat spaced apart, the two headers to which the respective banks are connected being nipped together at 18. The boiler tubes are located

above the primary combustion chamber 19, 55 defined by the front and rear walls 20 and 21, respectively, of the setting.

A baffle construction for directing the gases across the boiler tubes, comprises a roof baffle 22 supported upon the lower bank 60 of tubes 10^b and extending forwardly from the headers 13, which are, in turn, sealed against the rear wall 21, and a transverse baffle 23 extending upwardly from the front 65 end of the roof baffle 22 across the boiler tubes. A second baffle 24 is provided at the rear of the baffle 23, which is extended upwardly to the headers of the superheater 25 disposed above the boiler tubes, as shown, and extends downwardly across only a part 70 of the tubes, in a known manner.

In order to provide means for cooling the soot-blowing element, the front end of the roof baffle 22 comprises roof pieces 26 formed of a material, such as cast iron, 75 having good heat conductivity, which pieces are supported on and closely contact with the boiler tubes of the lower bank 10^b. The transverse baffle 23 comprises a metallic member 27 located at the lower portion 80 thereof and extending across the baffle, as shown in Fig. 3, which, in the form here shown, rests on the metallic roof pieces, and which is held in position by lugs 26^a extending upwardly from the roof pieces, 85 the lower face of the member 27 being bevelled, as shown, to form a close fit with the roof pieces. It will be understood, however, that the member 27 may be made integral with the roof pieces 26. The front side 90 of the member 27 is preferably provided with a recess 28, preferably semi-circular in form, as shown, which is adapted to receive a tubular soot-blowing element 29 provided with nozzles 30 extending through its wall, and through which steam is blown to 95 remove deposit from the tubes. It will be understood that the soot-blowing element 29 is supported at its ends in a known manner, and means are provided for rotating the same. The soot-blowing element is supported at intermediate points by brackets 100 31, which extend upwardly from the member 27, and preferably are formed integral therewith, the brackets being provided with 105 concave faces 32 within which the circular soot-blowing element is seated and in which it may be rotated.

Since the metallic member 27 is in thermal engagement with the water tubes through the metallic roof pieces 26, the member is kept comparatively cool, and it is in sufficient proximity to the soot-blowing element to exert a substantial cooling influence thereon, thereby greatly increasing the life thereof. Moreover, the soot-blowing element is protected from the intense heat of the furnace gases flowing upwardly through the first pass across the tubes by the roof pieces 26, which extend forwardly beyond the baffle 23, and which serve to cut off radiant heat from the soot-blowing element which is located above the roof pieces.

The front furnace wall 20 is preferably provided with an opening 33 adjacent to the lower tubes and closed by a door 34 which affords access for the removal of any slag or other deposit which may form on the tubes, and particularly the lower ones, where slag is most likely to form.

In Figs. 4 and 5, in which similar parts are indicated by similar reference characters, but with the letter "a" annexed, I have shown a modified form of my invention. The member 27 is here provided with an opening 28^b, the lower part 35 of which is preferably circular in form, and of greater radius than the soot-blowing element 29 which is seated therein, the soot-blowing element in this case directly engaging the wall of the opening 35. The recess 35 is made of a greater radius than the soot-blowing element in order that any slight irregularities in the latter will not cause it to bind while being turned.

In the form of my invention shown in Figs. 6 to 8, the member protecting the soot-blowing element is provided with a recess or opening 28^b, preferably circular in form, adapted to receive the soot-blowing element 29, the walls of the protecting member partially enclosing said element. The opening 28^b is preferably substantially larger than the tube of the soot-blowing element 29, in order that any warping of the latter may not cause the same to bind within the passage, and the tube of the element is preferably seated on the walls at the bottom of the opening, as indicated. The protecting member 27^b is here shown as integral with the base plate 26^b, which is seated upon and is in good thermal engagement with boiler tubes. The protecting members are preferably made in two sections for a single space between two of the boiler tubes, as best shown in Fig. 7. As stated, the walls of the protecting member are formed to enclose partially the soot-blowing element, and in the specific embodiment of my invention here shown, blocks 36 are provided which are preferably notched at one corner, as at 37, to engage a rib or raised portion 38 on the base 26^b, in order to hold the

blocks securely in position. The blocks 36 are formed with a concave surface, as at 39, which completes the cylindrical part of the recess or opening 28^b, the top of the blocks forming a tight fit, as at 40, with the wall 70 of the member 27^b above the recess. The upper and lower walls of that portion of the recess 41 (See Fig. 6) between two blocks are preferably flared, as indicated at 42. Tiles 43 are preferably laid on the tubes 75 in front of the base part 26^b of the protecting member. The centers of the nozzles 30 of the soot-blowing element 29 are preferably opposite the centers of those parts of the recesses formed between the blocks 36 so when the soot-blowing element is in its normal position.

The removable blocks 36 which come in front of the protecting member 27^b may be made integral with the protecting member 85 27^b. When this is done, the soot-blowing element must be introduced from the sides of the setting, whereas with the blocks 36 made removable, it may be placed in position by introducing it into the furnace, and 90 after passing one end through the side wall, laying it in place in the recess or opening 28^b. It is advantageous in most cases to introduce the soot-blowing element into the furnace and then lay it in place in the recess or opening 28^b, as the aisle room between boilers is usually insufficient for introducing the complete element directly from the side of the boiler into the recess or opening 28^b. Where the blocks 36 are 100 made integral with the protecting members 27^b, it would usually be necessary to divide the soot-blowing element into several pieces 105 in order that it might be introduced in lengths short enough to be handled in the aisle width, and this would make it necessary to employ joints in the soot-blowing element, which are objectionable.

Preferably, half or more of the entire length of the soot-blower pipes come inside 110 and are completely surrounded by cast iron, or other good heat conducting material, which forms a shield for the soot-blowing element. Any heat absorbed through radiation for that part of the soot-blowing element which is not completely surrounded by the protecting member, is conducted away to the protecting member, and the soot blowers are thereby prevented from being overheated.

What I claim and desire to secure by Letters Patent of the United States is:

1. In a steam boiler having horizontally extending water tubes and a furnace below the same, means for directing the furnace 125 gases upwardly across the horizontally extending water tubes, a metallic member located in the lower portion of the upward transverse pass, said member lying on the upper surface of a lower row of water tubes 130

and having extended surfaces in good thermal contact with said tubes, and a rotatable soot blower in close and extended thermal engagement with said metallic member 6 whereby the water in said tubes prevents overheating of the soot blower.

2. In a steam boiler having horizontally extending water tubes, an angle baffle lying over certain of the water tubes and having 10 its upward projection extending across the water tubes, a metallic member located in the lower portion of the first transverse pass of the gases, said member lying on the tops of water tubes and having extended surfaces 15 faces in good thermal contact therewith, and a rotatable soot blower having a good and extended thermal engagement with said metallic member whereby the water in said tubes prevents overheating of the soot 20 blower.

3. In a steam boiler comprising horizontally extending water tubes, means comprising a baffle for directing the furnace gases in transverse passes across the boiler 25 tubes, a metallic member associated with the lower portion of said baffle and in thermal contact with boiler tubes, and a rotatable soot-blowing element comprising nozzles located in the first transverse pass and in 30 thermal engagement with said metallic member, a metallic barrier in contact with boiler tubes being interposed in front of said element as regards the flow of the gases whereby said element is shielded from the gases, 35 the parts being constructed and arranged to cause the fluid issuing from said nozzles to sweep the portions of the tubes in the first pass.

4. In a steam boiler comprising horizontally 40 extending water tubes divided into an upper and a lower bank spaced apart, means comprising a baffle for directing the gases in transverse passes across the boiler tubes, the lower part of said baffle having a metallic 45 portion in thermal contact with boiler tubes, and a rotatable soot-blowing element comprising nozzles located in the first pass and between the two banks of tubes and in thermal engagement with said metallic portion 50 of the baffle, the parts being constructed and arranged to cause the fluid issuing from said nozzles during the rotation of the element to sweep the portions of the upper and lower banks of tubes located in the first pass.

5. In a steam boiler comprising horizontally 55 extending water tubes divided into an upper and a lower bank spaced apart, means comprising a baffle for directing the gases in transverse passes across the boiler tubes, 60 the lower part of said baffle having a metallic portion in thermal contact with boiler tubes, and a rotatable soot-blowing element comprising nozzles located in the first pass and between the two banks of tubes and in 65 thermal engagement with said metallic por-

tion of the baffle, a metallic barrier being laid upon tubes of the lower bank and in front of said element as regards the flow of gases whereby said element is shielded from said gases, the parts being constructed 70 and arranged to cause the fluid issuing from said nozzles during the rotation of the element to sweep the portions of the upper and lower banks of tubes located in the first pass.

6. In a steam boiler having horizontally 75 extending water tubes, an angle baffle located above certain of the tubes and having its upwardly extending portion crossing the tubes, a metallic member placed on top of certain of the water tubes and incorporated 80 in the baffle structure near its corner, the metallic member having extended surfaces in good thermal contact with the water tubes on which it lies, and a rotatable soot blower in extended and good thermal engagement 85 with said metallic member whereby the water in said tubes prevents overheating of the soot blower.

7. In a water tube boiler, a nozzled rotary soot-blower element extending across a row 90 of water tubes in the path of gases flowing across the tubes, and a metallic barrier extending parallel with the blower element throughout its length and having good thermal engagement with the water tubes, said 95 barrier having a longitudinal opening to receive said element and of sufficient diameter to permit the element to be rotated, and the walls of said barrier having openings opposite the nozzles of said element, said barrier 100 having a portion thereof located to prevent direct impingement of the element by the gases flowing past the element.

8. In a water tube boiler, a nozzled rotary soot-blower element extending across a row 105 of water tubes exposed to the radiant heat of the boiler furnace, and a metallic barrier extending parallel with the blower element throughout its length, said barrier being exposed to the radiant heat of the furnace and 110 having good thermal engagement with the water tubes, said barrier having an opening throughout its length to receive said element and of sufficient diameter to permit the element to be rotated, and the walls of said 115 barrier having openings opposite the nozzles of said element and in a part of the barrier other than that struck by the radiant heat rays.

9. In a water tube boiler, a nozzled rotary 120 soot-blower element extending across a row of water tubes in the path of gases flowing across the tubes and a metallic barrier extending parallel with the blower element throughout its length and having good thermal engagement with the water tubes, said 125 barrier having a longitudinal opening to receive said element and of sufficient diameter to permit the element to be rotated, and the walls of said barrier having openings oppo-

site the nozzles of said element, the blower element being supported by and in contact with the walls of said longitudinal opening, and said carrier having a portion thereof located to prevent direct impingement of the element by the gases flowing past the element.

10. In a water tube boiler, a metallic barrier comprising a plurality of metallic pieces arranged end to end across the boiler in the path of gases flowing across the tubes, each of said pieces having relatively long surfaces extending longitudinally of the water tubes and contacting throughout their length with one or more of the water tubes, and a nozzled rotary soot-blower element extending parallel with said barrier and supported and surrounded thereby to be rotatable therein, with elongated openings in said barrier opposite the nozzles of the element and permitting the projection of jets from the blower nozzles as the element is moved, said barrier having at least portions thereof located to prevent direct impingement of the

element by the gases flowing past the element.

11. In a water tube boiler, a metallic barrier in the path of gases flowing across the tubes and comprising a plurality of metallic pieces arranged end to end across the boiler, each of said pieces having relatively long surfaces extending longitudinally of the water tubes and contacting throughout their length with one or more of the water tubes, said pieces having recesses placed end to end to form a longitudinal space extending throughout the length of said barrier, a rotary nozzled soot-blower element resting in said space, and detachable caps extending over said element and arranged to permit said element to be rotated in said space, said caps being thermally connected to said pieces and having spaces between them opposite the nozzles of said element, and said barrier having a portion thereof located to prevent direct impingement of the element by the gases flowing past the element.

DAVID S. JACOBUS.
